MULTIPLE BUCK PRESS

Leo M. Kahn, Island Park, N. Y.

Original application April 16, 1943, Serial No. 483,230. Divided and this application February 25, 1949, Serial No. 78,250.

2 Claims. (Cl. 38—22)

1

This invention relates to a multiple buck laundry press.

This application is a division of my co-pending application Serial No. 483,230, filed April 16, 1943, now Patent No. 2,471,433, entitled "Laundry Machine."

Presently available domestic laundry presses are often lacking in flexibility, i. e. they are incapable of readily ironing or pressing all types of wearing apparel, as well as flat work. The reason for this arises usually from the fact that such presses have but a single non-interchangeable buck, suitable for only certain types of work, and which cannot readily be used for all types of work. Furthermore, in the use of such a press, the operator thereof must sit idly by while the press is operating, and accordingly her time during pressing operations is wasted; also, the press is idle while the buck is being unloaded and reloaded.

My laundry press comprises a double buck arrangement of such flexibility as to be readily able to operate on practically all types of ordinary wearing apparel and flat work, the buck arrangement being such that while one garment or piece of flat work is being pressed, another, of a different shape, may be loaded on the second buck. Furthermore, the machine occupies but a small amount of space in the laundry or kitchen, and requires but a small amount of power to operate efficiently.

While various types of double buck commercial presses have been proposed and even used commercially with a certain amount of success, such presses are not suitable for domestic use, being too bulky, expensive and difficult to use and not having the necessary flexibility necessary in a domestic press. Furthermore, it is usually difficult, if not impossible, to operate these commercial machines from a single station, to say nothing of a seated position.

It is among the objects of my invention to provide a laundry machine of the above nature which is simple, inexpensive and sturdy in construction, and which is capable of carrying out substantially all of the laundry pressing operations with a minimum amount of trouble, and at the same time with a high degree of efficiency.

Other objects will be in part apparent, and in part pointed out hereinafter.

The invention accordingly consists in the features of construction, combination of elements and arrangement of parts, all as will be exemplified in the structure hereinafter described, and the scope of the application of which will be indicated in the following claims.

2

In the drawing, wherein I have shown one form of my press.

Figure 1 is a front elevation of the press showing one buck in operating position and the other in a loading position;

Figure 2 is a top plan view of the press;

Figure 3 is a sectional elevation taken along the line 3—3 of Figure 1;

Figure 4 is an enlarged detail view, partially in section, of the buck locating detent;

Figure 5 is a top plan view of a modified form of the press;

Figure 6 is an enlarged fragmentary sectional elevation taken along the line 6—6 of Figure 5;

Figure 7 is an enlarged fragmentary sectional elevation taken along the line 7—7 of Figure 5;

Figure 8 is a wiring diagram of the control circuit for the machine; and,

Figure 9 is a wiring diagram of an alternate form of circuit for control of the heating elements in the presser head.

Referring first to Figure 1, the machine base is generally indicated at 20 and comprises a table-like support having legs 21 and a frame 22 supported on casters 23 to lend mobility to the machine. On frame 22 is supported a table generally indicated at 24 over which the bucks 25 and 26 may be moved to and from a head 27 supported from the bifurcated top 28 of an arm 29 detachably fastened to table 24. Illustratively and by mechanism to be described hereinafter, either of bucks 25 or 26 when in the position of buck 25 may be forced upwardly against head 27 so that an article of clothing disposed therebetween is pressed and at the same time heated by heater elements (not shown) in head 27. Thereafter the buck may be lowered to the position shown in Figure 1, whereupon it may be withdrawn to the dotted line position shown in Figure 2, whereupon buck 26 may be disposed beneath head 27. Thus, while one buck is beneath the head, the other may be unloaded and reloaded.

Frame 22 of the machine base has secured thereto a motor 30 (Figure 3), the armature shaft 31 of which is connected to a transmission or gear box generally indicated at 32. The output side of gear box 32 is connected as by a shaft 33 to a cam 34, the center of which is aligned with the axis of a vertical plunger or post 35, slidably disposed in a suitable bearing 36 (Figure 3) carried by frame 22. The bottom of plunger 35 rotatably carries a roller 38 which rides on cam 34 while to the top of this plunger is fastened a plate 37 which, when the plunger is in its lowermost position, as shown in this figure, rests within a suit-

3

able recess formed in table 24. As shown in Figure 2, plunger plate 37 is disposed centrally beneath the bifurcated top of arm 29 and accordingly is centrally located with respect to the center of mass of buck 25, for example, when this buck is in its operating position as shown in Figure 1. It will now appear that when motor 30 is energized it drives cam 34 through gear box 32 and causes plunger 35 (Figure 3) to rise and fall. Thus as the high spot of cam 34 is driven beneath plunger roller 36, buck 25 is forced upwardly with substantial pressure so as to be forced against head 27, properly to press any article of clothing disposed between the buck and head. By a control system to be described hereinafter, buck 25 is maintained in its uppermost or pressing position for as long a period of time as desired and is thereafter lowered to the position shown in Figure 1 to permit its replacement beneath head 27 by the other buck 26.

Thus, as shown in Figure 8, motor 30 has one side connected to a source 38 and the other side connected through a solenoid coil 39 to a stationary contact 40 of a switch generally indicated at 41. The movable contact 42 of switch 41 is connected by a line 43 to one side of a control switch generally indicated at 44, having a movable contact 45 engageable with a stationary contact 46 connected by leads 47 and 48 through a main switch 49 to source 38. This circuit controls the upward movement of the buck, as will be described.

Contact 49 is also connected by a lead 50 to a stationary contact 51 of a cam controlled switch generally indicated at 52, having a movable contact 53 on an arm 54. Arm 54 is connected by a line 55 to the arm 56 of another control switch generally indicated at 57. Switch arm 56 is connected to arm 44a of control switch 44 by a link 58 and also carries a movable contact 59 adapted to engage stationary contact 60 when switch 57 is closed. Stationary contact 60 is connected to source 38 by way of lines 48 and main switch 49. It will be noted that when control switch 57 is open, control switch 44 is closed, the former switch controlling the downward movement of the buck.

Switch 41 also includes an arm 41a and this arm, together with arm 54 of switch 52 is controlled, i. e. moved to and from its circuit closing positions in any suitable manner by cam 34. When cam 34 is in its uppermost position, as shown in Figure 8, switch 41 is open, while switch 52 is closed. When cam 34 has rotated 180° from this position, switch 41 is closed, whereas switch 52 is open. In operation, and assuming that plunger 35 and cam 34 are in the down position shown in Figure 3 so as to permit the placing of buck 25 beneath head 27, switch 44 (Figure 8) is closed. Of course, under these circumstances, cam 34 is 180° from the position shown in Figure 8, so that switch 41 is closed. Thus when switch 44 is closed, the following circuit is completed: source 38, motor 30, solenoid coil 39, contacts 40 and 42, line 43, contacts 45 and 46 of switch 44, lines 47 and 48, and main switch 49 to the other side of source 38. Motor 30 is accordingly energized and cam 34 is rotated as hereinbefore described. When the high spot on cam 34 reaches its uppermost position, as shown in Figure 8, contacts 40 and 42 are separated, thus breaking the circuit to motor 30 and accordingly stopping the cam in this position wherein the buck is pressed with maximum pressure against the head.

4

After the desired pressing period, link 58, which connects the arms of switches 44 and 57, is moved so as to open switch 44 and close switch 57. When switch 57 is closed, the following circuit is completed: source 38, motor 30, solenoid coil 39, contact 40, line 50, contacts 51 and 53 (which engage shortly after the initial movement of cam 34), line 55, contacts 59 and 60 of switch 57, line 48, main switch 49, to the other side of source 38. This circuit reenergizes motor 30 causing cam 34 to rotate until its high spot reaches its lowermost position when contacts 51 and 53 are opened, thus breaking the circuit to motor 30, accordingly restoring the buck to its original position, as shown in Figure 3. Thus it will appear that with main switch 49 (Figure 8) closed, the up and down movement of the buck is accurately controlled by operating the interlocked switches 44 and 57. Thus the operator of the press does not have to watch it closely in an attempt to determine when the buck is all the way up or all the way down.

Inasmuch as presses of this character are limited as to power consumption, it is desirable that the heating element in the head 27 (Figure 3) of the buck be deenergized, while motor 30 is operating, and it is to this end that I have provided solenoid 39 (Figure 8). In this figure, I have shown the heating element 61 of the head connected by a line 62 through main switch 49, to one side of source 38. The other side of heating element 61 is connected by a line 63 to a stationary contact 64 engageable by a movable contact 65, fastened to an arm 66 connected to the solenoid armature 67. Movable contact 65 is connected by a line 68 to the other side of source 38. Accordingly it will follow that when motor 30 is energized so also is the coil 39 of the solenoid. Upon energization of this coil, armature 67 is drawn to the left, as viewed in Figure 8, separating contacts 64 and 65, thus breaking the circuit of heater element 61. When, however, motor 30 is deenergized through the opening of either of switches 41 or 52, the solenoid coil 39 is also deenergized and its plunger 67 moves to the right to close contacts 64 and 65, thus energizing heater element 61. Thus the heating element is deenergized for but a few seconds during the lowering or raising of the buck, and accordingly its temperature is maintained at a substantially constant value. Preferably the heater element circuit includes a thermostat 69 which prevents the element from over or under heating, and a manually operable switch 61a by which the heater circuit can be broken when desired.

Under certain circumstances, it may be desirable to decrease the deenergization period of the heater element, and to that end I have provided the alternate circuit shown in Figure 9. In this circuit, element 61 is connected by a line 70 to one side of source 38, the other side of which is connected by a line 71 to a movable switch arm 72, carrying a movable contact 73 adapted to engage a stationary contact 74 connected by a line 75 through thermostat 69 to the other side of element 61. Switch arm 72 is normally maintained in a central position, wherein contacts 73 and 74 engage, by suitable springs 76 and 77 or the like. Switch arm 72 is pivoted, as at 78, and includes an extending foot 79 which lies in the path of a post 80 fastened to the buck plunger 35. In this view, the plunger is shown in its lowermost position wherein post 80 underlies foot 79. The post and foot are so spaced that they engage just before cam 34 raises plunger 35 to

its uppermost position, i. e. at the time when the buck first engages the head. When the high spot on cam 34 reaches its uppermost position, wherein the buck is exerting maximum pressure on the head and switch 41 (Figure 8) opens, post 80 rides past foot 79 permitting contacts 73 and 74 to close, thus closing the circuit to heater element 61.

As substantial power is necessary during the initial disengaging movement of the buck and head, post 80 engages foot 79 and separates contacts 73 and 74, breaking the heater element circuit as soon as downward movement of the high spot of cam 34 commences. However, as soon as post 80 rides past foot 79 during its downward travel, contacts 73 and 74 are reengaged to remake the heater element circuit. Thus it may be seen that the heater element is deenergized during only a small part of the upward and downward travel of the buck, and accordingly is not allowed to cool off for any appreciable length of time.

As noted hereinabove, one of the primary drawbacks to successful domestic laundry presses resides in the time lost between pressing operations. To a certain extent this has been overcome in commercial presses through the provision of tandem presses or double buck and head arrangements, but such presses are costly, bulky, complicated, space-consuming machines, and even so cannot easily be operated from a single position; i. e. in most cases the operator must walk from station to station in order to unload and load the inoperative buck while the other buck is under its pressing head. I have accordingly provided the table 24 shown in Figures 1, 2 and 3, which comprises a center section 81 which is preferably notched as at 82. Secured to frame 27 is a suitable bifurcated bracket 83 in which the lower end of arm 29 is pivotally secured as by a pin 84 which extends through the arms of bracket 83. A detachable locking pin 84a also extends through the arms of bracket 83 and through arm 29 to hold the arm in the full line position shown in Figure 3.

To the opposite sides of center section 81 of table 24 are respectively hinged leaves 85 and 86, and on the forward edges of these leaves are hinged respectively drops 87 and 88. Center section 81 of the table, leaves 85 and 86, and drops 87 and 88, preferably have a channel 89 (see also Figure 1) formed therein, and centrally of this channel is cut a guide slot 90 which, together with the channel, form a track or guideway for bucks 25 and 26. Preferably each buck is provided with a pair of guide pins 91 (Figure 3) adapted to extend into guide slot 90, and the base of the buck is provided with a suitable number of anti-friction rollers 92 to facilitate movement of the buck along channel 89. The base of each of the bucks is preferably kidney-shaped, as shown at 93 (Figure 2) to facilitate the travel of the buck around the curved portions of channel 89. It will now appear that channel 89 is generally U-shaped, thus permitting travel of buck 25 between its loading station on drop 87, and its operating station beneath head 27. Likewise, buck 26 is readily movable between its loading station on drop 88 (Figure 2) and its operative position beneath the head. It might be noted at this point that each of the bucks is preferably provided with a tray, such as tray 25a, which receives those portions of the garment mounted on the buck pad 25b which fall over the pad, thus

protecting these portions of the garment from becoming soiled by the rest of the machine.

As shown in Figure 2, I preferably provide a rotatable stool 94 which is located centrally of the machine and between the loading stations. The height of the stool is such, relative to the height of the table, that the operator's knees may comfortably extend beneath the table or the drops 87 and 88 and, illustratively, the edge of the stool may be three or four inches from the edge of the table and the drops. Thus, the operator may, without moving from the location of her working position, manually move bucks 25 and 26 into and out of operation position beneath the pressing head.

While I have disclosed and described a generally U-shaped path over which the bucks may be moved into and out of operative position beneath the head, I do not desire to be limited to a path of buck movement or travel of this precise configuration. Thus, it will readily appear that the buck guiding devices can be arranged in various ways to guide the bucks between their loading and operating stations in such a manner that the operator of the press is neither inconvenienced nor forced to rise from her seated position between the loading stations in order to move out of the way of the bucks.

Preferably center portion 81 of table 24 is provided with a forward portion 81a preferably provided with tracks or other suitable guides 95 and 96, which facilitate the movement of the particular buck as, for example, buck 25 which is in operative position under the head, from under the head and toward the operator for rearrangement of the garment on the buck, unloading of the buck, and reloading or any other operation which the operator wishes to perform. Thus the machine may be operated as either a double or single buck machine, neither mode necessitating movement of the operator from her seated position on stool 94. It will further appear that when two bucks are being used, what might be termed an "E-movement" may be advantageously resorted to under various circumstances. For example, with bucks 25 and 26 in the solid line position shown in Figure 2, the operator may be unloading and then reloading buck 26, while the garment on buck 25 is being pressed. It may be that she wishes to rearrange the garment on buck 25 prior to removal thereof to the dotted line position at her left. Accordingly the buck may be dropped in the manner heretofore described, and then rolled forward to the dotted line position 25f where the garment thereon is readily accessible to the operator for readjustment or removal. Thereafter this buck may be rolled back beneath the head and another pressing operation is performed. Thus, when the garment on buck 25 is finished, this buck may be dropped and manually moved to its loading station on drop 87, i. e. to a position beyond the dotted line position of buck 25. Thereafter, or indeed at the same time, buck 26 may be rolled into place beneath the head, whereupon the pressing cycle may be recommenced.

By reason of the provision of channel 89, guide slot 90, guide pins 91 and rollers 92, the bucks, although of substantial weight, to provide strength, may nevertheless be readily rolled into and out of operative position with respect to but a single pressing head, as desired. It will thus be seen that there is but little time lost between successive pressing operations, and while one gar-

ment is being pressed, another may be loaded on the idle buck.

As noted hereinabove, leaves 85 and 86 are hinged to table center section 81, and drops 87 and 88 are hinged to the leaves. Also, as arm 29 is pivoted to table 24 by the pin 84, the arm may readily be swung to an inoperative position by withdrawing pin 84a and swinging the arm about its pivot to the dotted line position shown in Figure 3. The top of arm 29 has a handle 29a (Figures 1 and 2) by which the arm may be pushed backward from its full line position in Figure 3 so as to move head 27 away from the top of the buck to enable the operator to rearrange or replace the article on the buck. Arm 29 may be held in this retracted position by a suitable chain or latch (not shown) which may be disconnected when the arm is moved to its dotted line position. Also, head 27 is preferably removably attached to the top 28 of arm 29 so that if desired the head may be removed or replaced, as the case may be. Thus it will appear that through the provision of the hinged leaves 85 and 86, hinged drops 87 and 88, and the removable arm 29, these several parts of the machine may be folded into the dotted line positions shown in Figures 1 and 3, so that with the parts so folded away the machine takes up but little room and may readily be rolled into a small corner of the laundry or kitchen, wherever the machine is used, and thus be disposed out of the way, or used as a utility table, if so desired. Suitable pivoted supports 98, 99, 100 and 101 (Figure 1) are provided to hold the leaves and drops in their unfolded position when the machine is in use.

As best shown in Figures 2 and 4, each of the bucks, as for example buck 25, is provided with a notched plate 102, the notch 102a of which receives a spring-biased detent 103 reciprocably mounted in bracket 104 and biased to the right, as viewed in Figure 4, by a spring 105. Bracket 104 is preferably fastened to arm 29 near the bottom thereof (see Figure 3) in such a position as properly to position buck 25 (Figure 2) beneath the pressing head 27. Thus the operator does not have to rely on her judgment in properly positioning the buck beneath the head, but merely rolls it into its approximate position so that the detent 103 and the notch in plate 102 may engage.

It will now appear that having placed one of the two bucks, for example buck 25 (Figure 2) in operative position beneath the head, the operator merely closes switch 44 (Figure 8) which may be located on the machine in any suitable and readily accessible position, whereupon the buck is forced upwardly against head 27 (Figure 1) into its pressing position, wherein it is automatically maintained for as long a period as desired, while the other buck 26 is being unloaded and re-loaded. When the pressing operation is finished, the operator merely closes switch 57 (Figure 8) at the same time opening switch 44, causing the buck to fall to its lowermost position whereupon it may be removed and the other buck rolled beneath the head.

It is desirable periodically, particularly after the bucks have been in operation over an extended period of time to dry, or at least partially dry the pad on the buck. To this end, and as shown in Figure 8, I have provided a bypassing circuit comprising leads 106 and 107 and a switch 108. Lead 107 is connected to one side of source 38 and one side of switch 108, while lead 106 is connected to the other side of switch 108 and to one side of motor 30. Thus when switch 108 is closed,

closed, motor 30 operates continuously, regardless of the position of the buck switches 44 and 57, thus causing the buck beneath the head to rise and fall steadily until switch 108 is opened. This intermittent engagement of the buck pad with the head suitably removes the excess moisture from the buck pad. As noted in Figure 8, switch 108 is mechanically coupled to switches 44 and 57 by a link 109, and to switch 49 by a link 151. Thus when switch 108 is closed, switch 49 is opened, thus breaking the circuit to heater coil 61.

In Figures 5, 6 and 7, I have shown a modified form of my double buck laundry press. In this form I utilize the buck raising and lowering devices, as described hereinabove. In the Figure 5 form, however, I provide a table generally indicated at 110 on the sides of which are hinged leaves 111 and 112, which may be folded down for storage purposes, as hereinbefore described with respect to leaves 85 and 86 (Figure 2). As shown in Figures 6 and 7, base frame 22 is provided with a journal 113 in which is rotatably disposed a post 114 which may be held in proper operative position by a nut 115 threaded on the bottom end of the post. The upper end of post 114 has a head 116 and between this head and the top of journal 113 are the hubs 117 and 118 of a pair of arms generally indicated at 119 and 120 (Figure 5). These arms are respectively joined to their hubs by goosenecks 121 (Figure 6) and 122 (Figure 7) so that the arms lie in the same horizontal plane. Hub 117 of arm 119 is provided with an operating handle 123 (Figure 6) and as shown in Figure 7, the two arms 35 may be coupled together in 90° relationship by a spring-pressed pin 124 extendable through flanges 125 and 126 formed on the hubs of the upper and lower arms, respectively. Thus when pin 124 extends through these flanges, the arms are held 90° apart and accordingly pivot together about the axis of post 114. When pin 124 is withdrawn, however, the arms may be pivoted separately so that either may be used. Otherwise arms 119 and 120 are identical, and accordingly arm 119 only will be described in detail hereinafter.

As shown in Figure 5, arm 119 is provided with an elongated slot 127 which extends from a point adjacent the inner end of the arm to a point 128 adjacent a rectangular opening 129 formed on the outer end of the arm. A continuation 128a of slot 127 is provided adjacent the outer end of the arm, this slot and opening 129 being provided for a purpose to be described.

Bucks 25 and 26 are in general similar to those hereinbefore described, but differ in that, for example, buck 25 (Figure 6) is provided with a pair of cups 130 and 131 in which are respectively disposed the upper ends of guide pins 132 and 133 provided with suitable heads between which and the bottom of pan 25a are disposed springs 134 and 135. Pins 132 and 133 extend respectively through slot 127 and slot extension 128a when buck 25 is in operative position, wherein they are held by heads on the lower end of the pins. Thus 60 the buck may move upwardly a limited but sufficient amount, upon upward movement of vertical plunger or post 35, the vertical plunger or post preferably having a table 136 fastened to the upper end thereof which extends through opening 129 upon upward movement of the plunger. When the plunger is moved down to the position shown in Figure 6, springs 134 and 135 force buck 25 downwardly until it again rests on arm 119.

As shown in Figure 5, the top 28 of presser 75 head supporting arm 29 overlies opening 129 in

arm 119 so that the presser head will overlie the buck when the buck is in operating position.

Arm 120 movably supports buck 26 which is shown in the full line position, i. e. the loading position in Figure 5. It will now appear that when the machine is operated, arms 119 and 120 are moved to the position shown. Subsequent to the pressing operation on buck 25 and the reloading of buck 26, buck 25 is dropped, as described above, and may thereafter be moved to the dotted line position for the same purposes as described in connection with the press shown in Figure 2. With the bucks in their full line positions (Figure 5) arms 119 and 120 may be pivoted counterclockwise until buck 25 has moved 90° from the position shown, where it will overlie table leaf 111. This movement moves buck 26 into position under the presser head, whereupon the pressing and loading cycle may be recommenced.

To facilitate this back and forth movement of arms 119 and 120, each of the arms preferably has attached thereto a pair of rollers 138 which roll along the top of table 110 as the arms are moved, accordingly supporting the arms and bucks. Here again it will appear that the operator seated on stool 94 may remain so seated during the pressing and loading operations without the necessity of moving to completely operate the machine.

As many possible embodiments may be made of the above invention, and as many changes might be made in the embodiments above set forth, it is to be understood that all matter hereinbefore set forth or shown in the accompanying drawing is to be interpreted as illustrative and not in a limiting sense.

I claim:

1. In apparatus of the character described, in combination, a U-shaped table support with a U-shaped guide track centrally disposed thereon, said table support and guide track defining an operating station at the base of the U and a loading station adjacent each end of the U, a pressing head secured to said table support and extending over said operating station, a pair of bucks movably mounted on said table support and each having means cooperating with said guide track whereby each may be moved from one of said loading stations to a position on said operating station adjacent said head and back again, and means for relatively moving said

head and a buck positioned adjacent said head toward one another to press an article disposed therebetween, whereby an operator may move either of said bucks between said operating station and a loading station without moving from a position between the legs of the U.

2. In apparatus of the character described, in combination, a U-shaped table support defining an operating station at the base of the U and a loading station adjacent each end of the U, a pressing head secured to said table support and extending over said operating station, a pair of bucks movably mounted on said table support, a guide track on said table support for restricting movement of said bucks, said guide track defining a U-shaped path extending from each of said loading stations to pressing position on said operating station adjacent said head, and a straight path communicating with said U-shaped path and extending from said pressing position to a point near the edge of said table support between the ends of the U, and means for relatively moving said head and a buck positioned adjacent said head toward one another to press an article disposed therebetween, whereby an operator positioned between the legs of the U may manipulate each buck along said U-shaped path between said loading and operating stations and draw a buck in operating position toward herself along said straight path thereby permitting alternate loading and pressing with each buck without the operator moving from between the legs of the U.

LEO M. KAHN.
